UNITED STATES PATENT OFFICE.

CHARLES D. ROGERS, OF PROVIDENCE, RHODE ISLAND, ASSIGNOR TO THE AMERICAN SCREW COMPANY, OF SAME PLACE.

DIE FOR POINTING AND CUTTING OFF NAILS, &c.

SPECIFICATION forming part of Letters Patent No. 393,519, dated November 27, 1888.

Application filed June 14, 1888. Serial No. 277,085. (No model.)

To all whom it may concern:

Be it known that I, CHARLES D. ROGERS, a citizen of the United States, residing at Providence, in the county of Providence and State of Rhode Island, have invented certain new and useful Improvements in Pointing and Cutting-Off Dies; and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

In the manufacture of screw-blanks, wire nails, and other analogous articles which are produced from a coil of wire the usual practice heretofore has been, so far as I am aware, to sever the blank from the wire by means of actuated dies which are so formed that the end of the coil is left substantially square, the dies at the same time producing a pyramidal-shaped point on the adjacent end of the blank. An objection to such form of dies is, more especially in the case of blanks which are to be headed, that the end of the wire upon being subjected to the action of the swaging-dies or heading-hammers has a tendency to bend toward one side of the die, thereby producing heads in which the metal is not uniformly distributed, and resulting in irregular-formed heads. Another objection to said dies is that they produce on the blank a point which (in case the point of the blank is to be screw-threaded) necessitates subjecting it to the action of mechanism adapted to reduce it to a cone shape prior to being acted upon by the threading-dies.

The objects I have in view in the invention illustrated herewith are to produce a cutting-off die of such form that when two of them are suitably mounted and operated the action of the dies in severing the blank from the wire forms a cone-shaped point having a compressed surface. At the same time the dies produce a rounded or globular form on the end of the standing wire, all as will be hereinafter more fully set forth and claimed.

In the annexed two sheets of drawings, Figure 1 represents a plan view of a portion of a

machine for making screw-blanks and having my improved cutting-off dies mounted therein. Fig. 2 is a partial central sectional view taken on line *x x*. Fig. 3, Sheet 2, is a horizontal sectional view enlarged, showing the dies at the termination of their movement and having the pointed blank between them. Figs. 4, 5, 6, and 7 represent views of the die. Fig. 8 is a perspective view of the end portion of the wire, showing the rounded end formed by the dies; and Fig. 9 is a perspective view of the fins or waste stock resulting from the action of the dies in pointing a blank and severing it from the wire.

In an application for Letters Patent filed by me in the United States July 7, 1887, Serial No. 243,657, I have shown and described at length an organized machine for producing headed screw-blanks. I make no claim therein to any specific form or construction of the cutting-off dies which sever the blanks from the coil of wire.

By referring to the drawings accompanying my present application it will be seen that I have shown in Sheet 1 a portion of a machine arranged more especially for the manufacture of wood-screw blanks, the mechanism illustrated being introduced to convey a better idea of the relation of my improved cutting-off dies to the heading hammers, &c.

In said drawings, *H* indicates a holder, in which a series of heading-hammers, *h*, are mounted. The holder is adapted to be intermittently moved up and down and also to reciprocate back and forth. The wire *w* is fed into the machine by means of dogs *d*, then through the tubular guide *c*, mounted in the front frame, *B*, of the machine, past the gripping-clamp *g'*, and through the adjustably-mounted die *D*. The faces of the said hammers *h* are made progressive—that is to say, the first to act upsets the metal in the die *D* and forms a preliminary head upon the end of the wire, the next reduces the head nearer to form, at the same time disposing the metal with reference to the slot to be produced, and the third (when three hammers are used) finishes the head, including the slot. After the head is formed, the feeding mechanism forces the headed wire from the die *D* and feeds it ahead

the desired distance to produce the blank, after which the cutting-off dies A, mounted on opposite sides of the machine in guided carriers or holders b, are forced toward each other simultaneously by operating mechanism, thereby, when the dies are brought together, acting to point the blank and sever it from the wire. The dies in retreating permit the blanks to fall from them.

I would state in passing that the blanks produced are finished complete (with the exception of the screw-thread) when dropped from the dies, no seam or fin being visible. The nick or slot for the screw-driver is, as before stated, formed in the head by the action of the heading-hammers.

I will now more particularly describe the novel features of my improved cutting-off dies.

In the drawings, A designates one of the dies as a whole, which are used in duplicate. The inner end or cutting-face of the die A is provided with a central cone-shaped recess, r, (one-half being in each die,) in which the end 25 of the blank is swaged. The lower side of the die is provided with a concavity, v, communicating with the apex of the recess r. The circumscribing edges n of the recesses r and v are sharpened, the metal being cut well back therefrom to afford clearance, as clearly shown in Fig. 5. By means of this construction it will be seen that when the dies are brought together upon a piece of wire their action is not only to point and sever the blank a, but at the same 35 time they produce a rounded or globular form, w', on the end of the standing wire w. (See Fig. 3.)

In the process of making the blanks the dies A are so set with relation to the solid die D 40 that a space, s, is left between the adjacent sides of the dies A D, as indicated by Fig. 3. This space corresponds substantially with the length of wire protruding from the face of the die D to be upset into the cavity u to form the head i of the next blank. By means of the rounded portion w' the wire is centralized and upset more uniformly by the heading-hammers h. Unless the rounded end be given to the wire the latter has a tendency to "cripple" 45 or to bend toward one side of the die, thereby producing imperfect blanks, or, in other words, blanks in which the metal of the heads is unequally distributed.

The dies A in the operation of pointing a 50 blank first act upon the wire by means of the

sharpened edges n, which force a portion of the metal of the wire outwardly from them, and at the same time produce a preliminary point. The continued and final action of the dies causes the conical cavity r thereof to compress and elongate the metal and form the cone-shaped point p upon the end of the blank, and also, as before stated, shaping the adjacent end w' of the wire, as clearly shown by Fig. 3.

The waste metal produced during the foregoing operation is represented by Fig. 9, the relation of the blank and wire thereto being indicated by dotted lines.

I claim as my invention—

1. A cutting-off die of the class hereinbefore described, having its working-face provided with a point-forming recess, and also having a cavity arranged to produce a convex-shaped end upon the wire, substantially as set forth.

2. A combined pointing and cutting-off die having a cone-shaped cavity and a concave recess communicating with said cavity formed in its working-face, and having the circumscribing edges of the die-cavities adapted for cutting, substantially as shown and described, and for the purpose hereinbefore set forth.

3. In a machine for making wood-screw blanks, the combination, with wire-feeding mechanism, a mounted heading-die, and actuated heading-hammers, of a pair of reversely mounted and actuated cutting-off dies having the working-faces constructed to engage the wire and reduce it to a cone-shaped form, and at the same time sever the blank and produce a convex shape on the end of the wire contiguous to the blank's point preparatory to upsetting the metal into the heading-die, substantially as hereinbefore described.

4. The combination, in a screw-blank machine, of a mounted solid heading-die and two suitably-mounted cutting-off and swaging-dies, A, having the working or meeting faces thereof provided with a cone-shaped recess or mold, r, communicating with or in close proximity to a concave recess, v, formed in the lower edge of the dies, substantially as shown and described, and for the purpose hereinbefore set forth.

In testimony whereof I have affixed my signature in presence of two witnesses.

CHARLES D. ROGERS.
